UNITED STATES PATENT OFFICE.

WILLIAM A. E. PFAFF, OF KANSAS CITY, MISSOURI.

SANITARY DOUCHE.

1,384,210.

Specification of Letters Patent. Patented July 12, 1921.

Application filed July 10, 1919. Serial No. 309,865.

To all whom it may concern:

Be it known that I, WILLIAM A. E. PFAFF, a citizen of the United States, residing at Kansas City, in the county of Jackson and State of Missouri, have invented certain new and useful Improvements in Sanitary Douches, of which the following is a specification.

This invention relates to a sanitary douche, and has for its object to produce an instrument for applying a fluid or solution for washing or medicinal purposes to internal organs of the body. A further object is to produce such an instrument for draining the fluid from such organs by a separate passage and thereby insuring the instant removal of the contaminated fluid or solution and hence the effectiveness of the treatment.

With these general objects in view the invention consists in certain novel and useful features of construction and organization of parts as hereinafter described and claimed; and in order that it may be fully understood reference is to be had to the accompanying drawing, in which:

Figure 1, is a perspective view of a douche embodying the invention in the preferred form.

Fig. 2, is a view partly in side elevation and partly in central section of the douche.

Fig. 3, is a cross section taken on the line III-III of Fig. 2.

Fig. 4, is a fragmental view of a modified form of the instrument.

In the said drawing, 1 indicates a tube provided at its front end with a nozzle comprising a tubular head 2 of slightly larger diameter than and screwed upon tube 1, and a deflector 3 having a hollow threaded stem 4 screwed into the head, the bore of the latter being enlarged at its front end to provide a chamber 5 and a flared end 6. The inner side of the deflector is beveled at 7 to substantially parallel the flared end 6 of the head, and the stem 4 is provided with an external enlargement 8 to fit against the base of the enlargement 5 of the bore of the head and thereby insure the production of a slight space between the beveled extremity 9 of the head and the beveled rear side of the deflector. The said stem between the deflector and the enlargement 8 is provided with one or more apertures 9 through which water or a solution entering the tubular stem escapes from the nozzle and is caused by the beveled end 6 of the head and the

juxtaposed deflector, to escape in the form of a thin cone-shaped sheet.

Secured upon the rear end of the tube 1 is a coupling 10 for a flexible hose 11 for supplying water under pressure from any suitable source, such, for example, as a hot water bag.

12 is a tubular sheath of substantially greater diameter than and fitting concentrically around tube 1, the front end of the sheath preferably constituting a slightly enlarged and forwardly tapering dilator 13 so disposed with relation to the nozzle, that the discharge of water or solution from the latter shall impinge against the inner side of said dilator within its flared front end or mouth 13a.

The dilator is provided internally with a forwardly facing shoulder 14 forming a seat for a spider 15 fitting on the tube 1 and engaged by the rear end of the nozzle thereof.

16 is a frustum shaped cap fitting with a water-tight joint on the rear end of the sheath and on the tube 1, the joint of the latter being made water-tight by the interposition of a gasket 17. The cap is provided with a drain nipple 18 having a spherical head 19 for convenient attachment with the end of a drain tube 20 leading to a suitable receptacle, not shown.

To use this douche it is inserted in the organ to be cleansed or medicinally treated and distends the same, the tissues or membranes being therefore smoothed out in effect, so that their entire surface adjacent the dilator are accessible to water or solution discharge from the nozzle. As the instrument is advanced into the organ the entire inner surface thereof is gradually distended or unfolded and brought under the force of the spray, the spraying action continuing as the instrument is withdrawn so that the organ for the length of the inserted part of the instrument, receives a second treatment.

During the operation described, the used water or solution escapes in a continuous stream through the sheath and thence from the cap thereof and into a suitable receptacle, it being understood that the hose 20 may be employed if necessary. To insure the most effective cleaning operation, the liquid under pressure may be permitted to pass through the instrument intermittently, and thereby in the interval, permit the

organ and the instrument to be thoroughly drained.

With the type of instrument shown by Fig. 4, the operation is the same except that 5 the dilator 21 makes no provision for drainage. The instrument therefore must be withdrawn after each charge of liquid passes through it to permit of natural drainage. This device will operate effectively but is 10 not as sanitary or convenient in use as the construction embodied in Figs. 1 to 3 inclusive.

From the above description it will be apparent that I have produced a device of the 15 character described which possesses all of the features pointed out as desirable, and I wish it to be understood that while I have described and claimed the preferred embodiment of the same I reserve the right to 20 make all changes properly falling within the spirit and scope of the appended claims and the principle of construction involved.

I claim:

1. A douche comprising a tube having a 25 nozzle for discharging a conical sheet of liquid forwardly and outwardly, a hose for supplying liquid to the tube, and a sheath fitting over and spaced from and adapted to receive and direct the discharge from the 30 tube and to also receive and drain off the contaminated liquid.

2. A douche comprising a tube having a nozzle at its front end, a hose coupled to

the rear end of the tube, a sheath fitting around and spaced from and projecting beyond the front end and terminating short of the rear end of the tube, and provided near its front end with an internal forwardly facing shoulder, a spider centralizing the tube and sheath and fitting between and against the said shoulder of the latter and the nozzle, a cap fitting on the tube and closing the rear end of the sheath and provided with a drain opening, and means for sealing the rear end of the cap around the 45 tube.

3. In a douche, a tube provided with a nozzle comprising a head having a longitudinal bore enlarged at its front end and flaring at its front extremity, and a deflector provided with a stem fitting in the bore of the head and with a shoulder engaging the bottom of the enlarged part of the bore to space the deflector from the front extremity of the head; said stem having a chamber open at its rear end and a discharge aperture connecting said chamber with the enlarged part of the bore of the head, in combination with a sheath fitting around and spaced from the tube and provided at its front end with a flaring mouth, a cap closing the rear end of the sheath, and a drain nipple connected to said cap. 55 60

In testimony whereof I affix my signature.

WILLIAM A. E. PFAFF.
